US00D726173S

(12) United States Design Patent
Kim et al.

(10) Patent No.: US D726,173 S
(45) Date of Patent: * Apr. 7, 2015

(54) COVER FOR MOBILE PHONE

(71) Applicant: Samsung Electronics Co., Ltd.,
Suwon-si (KR)

(72) Inventors: Yoon-young Kim, Seongnam-si (KR);
Min-a Oh, Gwangju-si (KR)

(73) Assignee: Samsung Electronics Co., Ltd.,
Suwon-si (KR)

() Term: 14 Years

(21) Appl. No.: 29/476,471

(22) Filed: Dec. 13, 2013

(30) Foreign Application Priority Data

Sep. 30, 2013 (KR) 30-2013-0049567

(57) CLAIM

The ornamental design for a cover for mobile phone, as shown and described.

DESCRIPTION

FIG. 1 is a front perspective view of a cover for mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dot-dash broken line in FIGS. 1 and 2 represents a boundary of the claimed design. The dash-dash broken lines throughout the drawing figures depict unclaimed portions of the cover for mobile phone. The broken lines form no part of the claimed design.

1 Claim, 7 Drawing Sheets
